UNITED STATES PATENT OFFICE.

ERNEST DALTROFF, OF PARIS, FRANCE, ASSIGNOR TO CARON CORPORATION, OF NEW YORK, N. Y., A CORPORATION OF NEW YORK.

DESIGN FOR A BOTTLE.

Application filed January 31, 1924. Serial No. 8,494. Term of patent 14 years.

To all whom it may concern:

Be it known that I, ERNEST DALTROFF, a citizen of the Republic of France, residing in the city of Paris, Republic of France, have invented a new, original, and ornamental Design for a Bottle, of which the following is a specification, reference being had to the accompanying drawing, forming a part thereof.

In the drawings,

Figure 1 is a perspective view of my design and

Figure 2 is a top view thereof.

I claim:

The ornamental design for a bottle substantially as shown.

ERNEST DALTROFF.
